Application February 25, 1939, Serial No. 258,494

9 Claims. (Cl. 219—47)

This invention relates to magnetic heaters and more particularly to magnetic heaters for heating thermoplastic or heat plasticizable materials in preparation for molding.

5 This application is a continuation-in-part of our copending application, Serial No. 181,250, filed December 23, 1937.

10 Electric heaters for heating thermoplastic material have been proposed before but when electro-magnetic forces have been used, the heating has been primarily induction heating produced by generating eddy currents in the heating body or through utilizing the heating body as the secondary element of a step down transformer.

15 We employ a varying magnetic field to produce the desired heat in the heater body, but we produce this heat through magnetic hysteresis effect as far as possible and minimize induction heating such as is generated by eddy currents in 20 the heater body.

Induction heaters are well known to the art, and are of two types. One type, operating on the transformer principle, produces heat by causing a heavy circulating current to flow through 25 the material to be heated and is generally used for melting brass and other non-magnetic materials. The second type, known as the high-frequency induction furnace, employing frequencies from about 360 to 100,000 cycles per second, produces heat by eddy currents. It is a characteristic 30 of the high frequency induction furnace to produce the greatest heat at the surface of the object to be heated, thus it has been used to advantage for heat treating machine parts such as 35 cams where the surface must be hardened without heating the inside of the part to the critical temperature.

The induction heating principle has been used in numerous applications where intense or rapid 40 heating is desired, and has been used in molding processes, as for heating rubber molds.

However, heating by eddy currents is inherently unsuited to the heating of thermoplastic material for injection molding, since it produces 45 surface heating. What is desired in a thermoplastic heater is a uniform heating throughout the heater body so that a maximum transfer of heat can be obtained without danger of burning the material. To accomplish this we employ a 50 principle which we shall term magnetic heating, which produces heat by hysteresis when a varying electro-magnetic field is impressed on a heater body made of a material having high coercive force. Moreover we take special steps to minimize 55 eddy current heating. Some eddy current

heating is unavoidable in such a structure, but the essence of our invention lies in making the hysteresis heating effect large compared to the heating by eddy currents, in contradistinction to induction heating where eddy currents are the 5 principal source of heat.

Thus by relying chiefly upon hysteresis losses for the production of heat, we accomplish uniform heating throughout the heater body with the result that every particle of the material subjected to heat, is uniformly heated. Where eddy current heating is relied upon, the heating is not uniform for the heating effect is a skin effect, the heat produced being greatest near the outer surface and decreasing to zero at the center. 15

The intensity of the heating can be readily adjusted as desired by varying the intensity of the magnetic field, as for example, by varying the applied voltage, or changing the number of turns in the coils. 20

It is thus evident that the effectiveness of our invention lies, in large part, in making the hysteresis effect large compared to the induction or eddy current effect, so that the desired heating will be essentially uniform throughout the body 25 of the heater. We have found it desirable, in order to make hysteresis large and eddy currents small, to employ a material having high coercive force and high resistance, to employ a low frequency magnetic field, and to so proportion the 30 magnetic heater that the flow of eddy currents is impeded; as is more fully set forth hereinafter.

Hysteresis "may be thought of as due to some kind of friction between the molecules of the magnetic material". The varying magnetic field 35 to which we subject the magnetic heater body causes each molecular magnet to reorient itself with the flux each cycle, and the resulting friction produces the desired heat. Certain materials possess high "magnetic friction" or are said 40 to have a high coercive force and such materials are highly desirable for our purposes since they produce the desired heat with magnetic fields of moderate intensity. Since the undesired eddy current heating is proportional to the square of 45 the flux density (other things being equal), it will be evident that it is very helpful to be able to employ weak fields. Magnetic steel alloys, such as are commonly used in permanent magnets, as a class exhibit the high hysteresis, high 50 coercive force and high retentivity which we desire. These may be magnet steel alloys as described and examples given on pages 294 to 298 inclusive, of the fifth edition of Standard Handbook of Electrical Engineers published by Mc- 55

5 Graw-Hill Book Company or may be other alloys as described and examples given on pages 1679 and 1680 of volume III of Hutchinson's Technical and Scientific Encyclopedia, published by MacMillan Company. By way of illustration, the following alloys may be used: Chromium steel; tungsten steel, and cobalt steel.

10 Eddy currents are circulatory currents in the magnetic body induced by the varying field, in much the same way that currents are induced in the secondary of a conventional transformer. These currents are inversely proportional to the specific resistance of the heater body, so that a material having high resistance is very desirable for the heater body.

15 Thus a material having high hysteresis and high resistance is very effective in producing uniform heating, and any metal or alloy exhibiting these characteristics would be suitable for our heater core provided that it has the necessary mechanical strength.

20 We also prefer to utilize alternating currents of relatively low frequency for producing the varying magnetic field. In a given magnetic heater of the type described, a reduction in frequency may lower the effect on the eddy current heating, but it will increase the hysteresis effect. Therefore a reduction in frequency makes the heating more uniform. Thus in contrast to 25 high frequency induction heaters where frequencies of 5,000 to 100,000 cycles per second are usual, we prefer to use commercial frequencies such as 60; 50; or 40 cycles per second. We do not wish to restrict ourselves to these frequencies however, as other uncommonly low frequencies, such as 10 cycles, are within the scope of this invention.

30 It was mentioned in a preceding paragraph the eddy currents are inversely proportional to the resistance of the path through which they flow, and the advantage to be gained from using a material of high specific resistance for the heater body was pointed out. It is also possible to increase the resistance of the eddy current path by 35 suitable shaping of the heater body, as by introducing slots to cause the currents to flow through a circuitous route, as is more fully described in our copending application Ser. No. 181,250 of which this is a continuation in part.

40 Other features of our invention reside in the provision of a perforated conduit heater and in the provision of an electro-magnetic field structure particularly suitable for magnetic heating.

45 An object of the invention is to heat thermoplastic material uniformly throughout.

50 Another object of the invention is to heat thermoplastic material magnetically.

55 Another object of the invention is to heat thermoplastic material magnetically while eliminating so far as is possible induction heating by eddy currents.

60 Another object of the invention is to utilize a magnet steel alloy having high coercive force as a magnetic heater.

65 Another object of the invention is to provide in a magnetic heater, a closed magnetic circuit including as one leg a magnetic heater body having high coercive force, and as other legs laminated sheet cores.

70 Other objects of the invention will be apparent from the following description and from the drawing.

75 A preferred embodiment of the invention will now be described with reference to the drawing, of which:

Fig. 1 is a view in longitudinal section, of one embodiment of an assembled magnetic heater incorporating features of this invention;

Fig. 2 is a sectional view along the lines 2-2 of Fig. 1, and

Fig. 3 is a sectional view along the lines 3-3 of Fig. 1.

The magnetic heater preferably is divided into two portions, the cylindrical portion 5 in which preliminary heating is accomplished, and the 10 tapering perforated or chambered portion 6 herein shown as having the converging bores or channels 7, and in the outer end of which the outlet nozzle 8 is screwed. Eight bores or channels 7 are shown in the tapering portion 6 of the 15 heater but it will be understood that the number of these channels may be varied and their shape modified within the scope of the invention. Both heater portions 5 and 6 are formed from magnet steel alloys having high coercive force in order 20 that suitable heat may be produced therein under the influence of a varying magnetic field as is hereinafter described.

The heater portion 6 is fitted within the cylindrical heater portion 5 and is attached thereto 25 in longitudinal alignment by cap screws 9 which extend through circular openings in a shoulder of the heater portion 6 and are screwed into tapped corresponding openings in the cylindrical portion 5. The entire heater comprising the two 30 portions 5 and 6 is supported from cooperating feeding mechanism by the cap screws 10, fragments of which are shown.

The cylindrical heater portion 5 contains a centrally located solid torpedo or pineapple 11 35 with walls equi-distantly spaced from the inner walls of the cylindrical heater portion 5 to form an annular passage 12 through which the thermoplastic material to be acted upon flows. The torpedo 11 is supported by a threaded end 13 40 which is screwed into a tapped opening in the central portion 14 of the converging heater 6, and performs the function of splitting smoothly and in stream-line flow, the body of thermoplastic material entering the channel 15, for passage into 45 the channels 7 which are in longitudinal alignment with the channel 12. The torpedo 11 is also preferably formed of magnet metal having high coercive force, or may be a permanent magnet and it provides relatively great surface contact with the thermoplastic material passing through the channel 12, and heats the material through hysteresis losses as do the heaters 5 and 6.

The torpedo 11 may be replaced with the annular plunger disclosed in the copending application of Charles S. Bird, Leon F. Marsh and Graydon Smith, entitled "Heating apparatus for injection molding machines."

The channels 7 in the heater 6 converge 50 throughout their length and meet in the common channel 38 which is located in alignment with the channel 31 in the nozzle 8.

The two shoulders 16 and 17 of the heater portion 5 are each cut away to provide, in the embodiment illustrated, ten equi-distant plane surfaces for receiving the radial legs 18 and 19 respectively, of bridge-shaped laminated sheet cores 20, which are fitted tightly against the heater 6. The cores 20 with their legs 18 and 19 55 and the cylindrical heater 5 form a closed magnetic circuit, of which one portion (20) is an electro-magnetic core and of which the other portion (5 and 11) is a coercive magnet core. For the purpose of this description and for the 60

claims, electro-magnetic and coercive magnet cores are defined thus: "An electro-magnetic core is a laminated core comprising metal sheets, such as silicon steel, in which all losses are kept as low as practical. A coercive magnet core is a magnetic core in which hysteresis losses are very high and eddy current losses are relatively low."

The electro-magnetic cores 20 with their legs 18 and 19 also form bridges around the cylindrical heater 5, and within the bridged spaces 27 between the legs 19 and 20 are supported the spaced annular coils 21, each coil containing a plurality of turns of wire, the coils being adapted to be connected electrically in series with respect to each other for energization from, for example, a 60 cycle alternating current source, though obviously other frequencies may be employed or the current may be pulsating or interrupted direct current.

The converging portion 6 of the heater likewise has in the embodiment illustrated, ten plane faces provided on each of its shoulders 22 and 23 for receiving the legs 24 and 25 of the electro-magnetic cores 26 which like the cores 20 are formed from laminated metal sheet. The cores 26 likewise bridge the spaces around the converging heater 6, and within the bridged spaces 28 between the legs 22 and 23 are supported the annular coils 29 which like the coils 21 are composed of a plurality of turns and which are adapted to be connected in series and to an alternating or pulsating direct current supply source.

The electro-magnetic cores 20 and the coils 21 are supported on the cylindrical heater portion 5 and the cores 26 and the coils 29 are supported on the heater portion 6 by suitable structure not herein illustrated, but which may be of the nature disclosed in the copending application of

40 Graydon Smith, Serial No. 259,201, filed March 1, 1939, and entitled Magnetic field structure.

The torpedo 11 is tapered to form with the outer heater portion 5 the diverging annular channel 12, as shown in Fig. 3, and the central portion 14 of the heater portion 6 is oppositely tapered to form the converging channels 7. The pointed end and tapering body of the torpedo serves to divide the incoming material into an annular stream and, together with the heat received from the walls, prepares the material for passage into the channels 7 as it moves through the passage 12. With this arrangement, minimum resistance to flow with maximum heating surface contact for the thermoplastic material, are provided.

In operation, low frequency alternating or pulsating direct current supplied to the coils 21 and 29 causes through the electro-magnetic cores 20 and 26 respectively, varying magnetic fields around and in the magnetic heaters 5 and 6 respectively and in the inner core or pineapple 11. By including the magnetic heaters 5 and 6 as elements in closed magnetic circuits, the varying magnetic field is produced much more readily and efficiently, thus reducing the current which the coils must carry for a given heating effect. The use of a closed magnetic circuit furthermore confines and directs the field, thus minimizing stray magnetic fields and consequent stray heating of other parts of the machine to which the heater is attached.

The cylindrical magnetic heater 5 serves as a preliminary heater and acts upon the solid thermoplastic material entering the channel 15 to soften it sufficiently for it to flow easily from the

channel 12 into the converging channels 7. The incoming material while in the preliminary heating stage is divided into an annular stream by the torpedo, as above described, preparatory to its introduction into the channels 7. The converging magnetic heater 6 then provides increased heating surface on the material and additional heat to reduce the material to the desired plastic condition for extrusion through the nozzle 8 to suitable molds or dies.

It will be apparent from the foregoing that we prefer that our heaters have as high a ratio as possible of hysteresis loss to eddy current loss. This may be accomplished by lowering the eddy current for a given hysteresis effect or by increasing the hysteresis effect for a given eddy current loss. Thus we produce uniform heating throughout the material being handled and so are able to provide the necessary heat without burning any portion of the material through the formation of hot spots.

While one embodiment of the invention has been described for the purpose of illustration, it should be understood that other material and arrangements of material may be suggested by those skilled in the art for providing magnetic heating through a high ratio of hysteresis loss to eddy current loss without departure from the essence of the invention. Moreover, while in describing the apparatus we have referred to its use in connection with the molding of thermoplastic materials, it is, of course, not limited to any particular type of material capable of being rendered plastic by heat, and the term "thermoplastic" is herein used in that broad sense.

Having thus disclosed our invention and described an illustrative embodiment thereof, we claim as new and desire to secure by Letters Patent:

1. A magnetic heater comprising a perforated 40 magnetic element adapted to receive and to heat thermo-plastic material and possessing the characteristic of having relatively high hysteresis losses and relatively low eddy current losses when subjected to a varying magnetic field.

2. A magnetic heater comprising a perforated magnetic element adapted to receive and to heat thermo-plastic material and possessing the characteristics of having a high ratio of hysteresis to eddy current losses when subjected to a varying 50 magnetic field.

3. A magnetic heater comprising a perforated magnetic element adapted to receive and to heat thermo-plastic material and possessing the characteristics of having relatively high hysteresis 55 and relatively low eddy current losses and having high electrical resistivity to the flow of eddy currents when subjected to a varying magnetic field.

4. A magnetic heater comprising an integral 60 cylindrical core and an integral hollow tapering core bolted together and providing a longitudinal passage, both of said cores being steel of high coercive properties, separate series of electro-magnetic bridges engaging the cylindrical and 65 tapering cores respectively, and separate series of electro-conductive coils disposed about the two cores within said bridges.

5. A magnetic heater for thermo-plastic material, comprising an integral core of steel having high coercive properties and having a passage longitudinally therethrough for said material, means providing a plurality of electro-magnetic bridges disposed about and engaging the core and having relatively low hysteresis losses 75

when subjected to a varying magnetic field, and electro-conductive coils disposed about the core within the bridges, whereby to heat said material uniformly, as it passes through the core, by relatively high hysteresis losses in the core.

5. 6. A device for heating thermo-plastic material, comprising a body of steel having high coercive properties and having a solid inner centrally disposed portion so spaced from the outer portion as to provide passage longitudinally through the body between the inner and outer portions for receiving said material, and means for producing relatively high hysteresis losses in said body for heating said material as it passes 10 through the body between said portions.

7. A device for heating thermo-plastic material, comprising a body of steel having high coercive properties and including an inner core providing an annular passage thereabout and extending longitudinally within the body and diverging to a predetermined position within the body, the body having a plurality of relatively small passages in communication with the annular passage at said position and converging 20 therefrom away from the annular passage to the exit end of the body, and means for producing hysteresis losses in the steel body for heating said material as it passes through the passages to said exit end of the body.

8. A device for heating thermo-plastic material, comprising a body of steel having high coercive properties and having passage longitudinally therethrough for receiving said material, the body possessing the characteristic of having relatively high hysteresis losses when subjected to a varying magnetic field, cooperating magnetic means possessing the characteristic of having relatively low hysteresis losses when subjected to said varying magnetic field, said means bridging a portion of the length of said body and forming with the same a closed magnetic circuit, and an electric winding in the bridged space between said means and the body adapted to be energized by a pulsating electric current for producing a varying magnetic field.

9. Heating apparatus for thermoplastic material or the like, comprising an elongated body of ferro-magnetic metal which exhibits high hysteresis loss when subjected to an alternating magnetic field, the body having a plurality of passages longitudinally therethrough for receiving said material and having non-conductive gaps between the passages to reduce eddy current therein, and means arranged to heat the body by subjecting it to electro-magnetic action.

GRAYDON SMITH.
ALBERT ALLEN.
